UNITED STATES PATENT OFFICE

CHARLES SYDNEY NASMYTH, OF SYDNEY, NEW SOUTH WALES, AUSTRALIA

FLUSH VALVE

Application filed September 4, 1929. Serial No. 390,403.

The invention relates to what are generally known as "silent flush valves" employed for sanitary purposes and more particularly to the class of such valves in which action is set up by the operation and release of a push button.

In such valves it is of importance that flushing water shall pass only when the push button has been operated and then released as otherwise it might be possible, by continuous pressure upon the push button, to waste a considerable quantity of water without producing a sufficient flow for flushing purposes. It is also important that approximately the same quantity of flush water shall be discharged notwithstanding differences of pressure in the main supply pipes.

My invention provides a simple flushing apparatus having the desired characteristics.

According hereto a main valve closing the flush pipe is integral with a plunger slideable in a cylinder.

Water from the main supply pipe fills the cylinder above the plunger and the main valve is kept upon its seat by pressure.

When the pressure above the plunger is reduced by means to be hereinafter described the pressure below it forces it upwards lifting the valve from its seat and permitting flushing water to flow from the supply pipe through the flush pipe.

The flushing continues until pressure above the plunger is restored by the percolation of water through a relatively small portway, the valve then returns to its seat.

I will now describe the details of my invention and the operation thereof by aid of the accompanying drawing wherein:

Fig. 1 is a central sectional elevation.

Fig. 2, a sectional plan on 2 2 Fig. 1.

Fig. 3, a sectional plan on 3 3 Fig. 1 and

Fig. 4, a sectional plan on 4 4 Fig. 1.

The cylindrical casing 1 has the lateral branch 2 to which the main water supply pipe is connected and a cylindrical extension 3 to which is connected the flush pipe 4.

A valve 5 seated upon the top of the extension closes the passage to the flush pipe.

A plunger 6 integral with valve 5 is re-

ciprocable in casing 1 and has upon it a cylinder 7 in which is a piston valve 8 adapted to close a central passage 9 extending through the plunger and through the main valve and which is also designed when in its normal position to close portways 10 at the lower end of cylinder 7.

The plunger as illustrated is provided with bucket leathers 25 but a plunger of any usual type may be substituted.

The valve 5 is guided by a tubular spindle 11 projecting below it and passing through a hole in a cross bar 12 in the extension 3.

Reciprocable within the upper end of cylinder 7 is a piston 13 fixed upon a spindle 14 passing through a packing gland 15 in the cover plate 16 and having upon its end a press button 17 slideable through the top of a cover cap 18 which screws upon the top of casing 1 and holds the cover plate in position. A bypass hole 19 passes through the piston 13.

A spiral spring 20 sleeved upon spindle 14 tends to project the press button and to raise the piston 13 to the top of cylinder 7.

A rubber washer 21 upon spindle 14 reduces shock when the piston rises to the limit of its stroke.

A small passage 22 in the casing leads from above plunger 6 to the branch 2 and is provided with an adjusting set screw 23.

A stud 26 projecting from the cover plate passes into a hole in the casing and ensures the correct position of the cover plate.

A passage 24 leading through the cover plate 16 to below valve 5 provides for the discharge of water which may happen to escape through the packing gland.

In operation pressure upon the press button forces the piston 13 into the cylinder 7 the water displaced passing through the bypass 19.

Removal of pressure upon the press button permits the piston to rise in cylinder 7 and the piston valve 8 is lifted by suction from its seat permitting water from above the plunger 6 to escape through the portways 10 and through the passage 9 to the flush pipe.

Pressure above the plunger 6 being thereby reduced it is forced up by the pressure below

it, the valve 5 is lifted from its seat and a rush of flushing water takes place from the main pipe through the flushing pipe.

Pressure above the plunger 6 is gradually restored by water passing through the restricted passage 22 until equilibrium of pressure being re-established above and below the plunger the main valve resumes its seat and the flow of water ceases.

10 The period during which the flushing continues depends upon the area of the passage 22 and this may be regulated as desired by the set screw 23.

I claim:

15 1. Flushing apparatus comprising in combination a cylindrical casing, a plunger reciprocable therein, a valve connected to the plunger adapted to close the opening to a flush pipe, a cylinder connected to the plunger provided with portways, a piston valve within the cylinder adapted to close a passage through the plunger and also the portways in the cylinder, a piston reciprocable within the cylinder and having a bypass passage, a rod to which the piston is connected, a push button upon the end of the rod, and a spring sleeved upon the rod, the casing having a passage way extending from above the plunger to the main water supply pipe substantially as and for the purpose specified herein and illustrated.

20 2. In flushing apparatus such as claimed in claim 1 the combination of a plunger, a valve connected thereto adapted to close a flush pipe, a cylinder upon the plunger, a piston valve reciprocable therein adapted to close portways in the cylinder and also a passage through the plunger and the valve, a piston reciprocable within the cylinder and having a bypass passage, spring means for returning the piston to its normal position, and means by which the piston is forced into the cylinder substantially as and for the purpose herein described and illustrated.

25 45 In testimony whereof I have signed my name to this specification.

CHARLES SYDNEY NASMYTH.
